Primary Examiner — Michael A. Pratt*Assistant Examiner* — Wendy Arminio(74) *Attorney, Agent, or Firm* — Adam P. Daniels, Esq.; Polsinelli LLP(57) **CLAIM**

The ornamental design for a sport training apparatus, as shown and described.

DESCRIPTION

FIG. 1 is a front perspective view of a sport training apparatus, shown in a position of use attached to an unclaimed goal drawn in broken lines.

FIG. 2 is a front perspective view of the sport training apparatus shown in FIG. 1;

FIG. 3 is a back perspective view of the sport training apparatus shown in FIG. 1;

FIG. 4 is a front elevation view of the sport training apparatus shown in FIG. 1;

FIG. 5 is a back elevation view of the sport training apparatus shown in FIG. 1;

FIG. 6 is a right side elevation view of the sport training apparatus shown in FIG. 1;

FIG. 7 is a left side elevation view of the sport training apparatus shown in FIG. 1; and,

FIG. 8 is a top plan view of the sport training apparatus shown in FIG. 1.

The broken lines showing a goal in FIG. 1 depict environment and form no part of the claimed design. All other broken lines depict portions of the sport training apparatus that form no part of the claimed design.

1 Claim, 7 Drawing Sheets(56)
